UNITED STATES PATENT OFFICE

2,602,437

HYDRAULIC PROFILER FOR TRUING
DEVICES AND THE LIKEWilliam L. Tancred, Springfield, Vt., assignor to
Jones & Lamson Machine Company, Springfield,
Vt., a corporation of Vermont

Application April 29, 1946, Serial No. 665,858

3 Claims. (Cl. 125—11)

1

This invention relates to a profiler for truing devices and the like, and has for an object to provide a hydraulically acting mechanism which will follow a pattern with great accuracy and with uniform feed.

A further object is to improve the mechanism by causing one valve to control the power feed in two right angularly related directions, the acceleration in one direction being always proportional to the deceleration in the other direction.

Still another object is to provide a mechanism in which the pattern-engaging tracer may be readily changed to suit the tool used for truing.

For a complete understanding of this invention, reference may be had to the accompanying drawings in which

Figure 1 is a view partly in top plan and partly broken away and in section, but omitting much of the hydraulic system, of a machine embodying the invention.

Figure 2 is a vertical sectional view on line 2—2 of Figure 1 and showing the hydraulic system somewhat diagrammatically.

Figure 3 is an elevation at the tool end of the machine.

Figure 4 is a vertical sectional view on line 4—4 of Figure 2.

Figure 5 is a fragmentary perspective view of the machine, most of the hydraulic connections being omitted.

Figures 6 to 9, inclusive, are diagrammatic longitudinal sectional views through the control valve and pattern in successive positions as the tracer traces a pattern.

Referring first to Figures 1 to 5, at 1 is indicated a support having a guideway 2 therein for the reception of a slideable carriage 3, this carriage being movable toward and from the device to be profiled, herein shown as a multi-ribbed grinding wheel 4 mounted on a shaft 5. The direction of motion of the slide 3 is thus one to feed the truing tool shown at 6 toward the grinding wheel 4 or to retract it therefrom. This carriage 3 is provided with a transverse guideway 10 within which is mounted for motion at right angles to the direction of motion of the carriage 3, a carriage 11. This carriage 11, in its turn, has a way 12 within which is slidably mounted a carriage 14, the carriage 14 and the carriage 3 thus moving in the same general direction and transverse to the direction of motion of the carriage 11. This carriage 14 has a post 15 projecting upwardly therefrom for mounting the tool 6. The direction of traverse of the carriage 11

may be termed the "traverse direction," while the direction of motion of the carriages 14 and 3 may be termed the "feed direction." The carriage 3 is normally held against motion in its 5 guideway but is adjustable thereon, this being effected by means of the adjusting screw 20 journaled in an upstanding ear 21 of the support 1 and threaded into an internally threaded ear 22 upstanding from the carriage 3. A knurled head 23 on the outer end of the screw 20 serves to facilitate turning of this screw to thereby adjust the setting of the carriage 3 for different sizes of work and as the work and tool are worn and trued away. The control of the tool 6 is provided 10 by a pattern and tracer shown at 24 and 25, respectively. One of these parts, herein shown as the pattern 24, is secured as by screws 26 to a bar 27, the ends of which are secured as by screws 28 to supporting posts 29 extending upwardly from the carriage 3 at opposite ends, so that the pattern is stationary in the direction of traverse but is adjustable with the adjustment of the slide 3. The tracer 25 is shown as fixed to the upper end of an arm 30 fulcrumed at its 15 lower end as at 31 on a pair of ears 32, one of which is shown in Figure 5, these ears projecting upwardly from the slide 14. The tracer 25 therefore partakes of the traverse motion of the tool, since the slide 14 is carried by the traverse slide 11, and it is also allowed a movement in the feed direction by its swinging mounting on the carriage 14 and through the feed motion of this carriage 14. It is normally held pressed against the edge of the pattern 24 by means which will 20 later be described.

30 The traverse motion of the tool 6 with respect to the work which comprises the grinding wheel 4, is produced by hydraulic mechanism, and this, as shown, is under the control of the operator who may determine the direction of such traverse, reversing it at will. The speed of such traverse, however, is automatically controlled, as will 35 later appear.

40 The means for moving the tool and tracer in traverse direction, as shown, comprises a hydraulic cylinder 35 fixed to the carriage 11 and carrying therein a piston 36 secured to a stationary piston rod 37 which passes through both ends of the hydraulic cylinder 35 and is secured 45 at its ends as by screws 38 to the supporting posts 29. The cylinder 35 is thus mounted for traversing motion, but since the posts 29 are carried by the carriage 3, motion of the cylinder 35 will 50 cause this carriage 11 to be moved in traverse direction.

The hydraulic power circuit for effecting such traversing motion may comprise, as shown in Figure 2, a tank 40 for the hydraulic liquid from which it is pumped by a pump 41 driven by a motor 42 past a flow control valve 43 into a pressure supply pipe 44. Any excess of pressure beyond that required at any particular time is vented back to the tank from the pump 41 through a suitable relief valve and the pipe 45. The hydraulic fluid under pressure passes from the pressure pipe 44 into the valve cylinder 46 which is shown as supported upon the hydraulic traverse cylinder 35. Within the valve cylinder 46 is a spool valve 47 from opposite ends of which extend control rods 48 through the end walls of the valve cylinder. These rods are shown as terminating in actuating knobs 49 by which the valve may be moved to one or the other of its control positions to determine the direction of traverse. As shown in Figure 1 the valve spool 47 is moved to a position where its central cannelle 50 directs the fluid under pressure through the pipe 51 into the end chamber 52 of the cylinder 35. Since the piston 36 is stationary, pressure within chamber 52 causes the cylinder 35 and the carriage 11 to be moved in the direction shown by the arrow A in Figure 1. The fluid at the opposite end of the cylinder 35 within the piston chamber 55 discharges through the pipe 56, end chamber 57 of the valve cylinder 46, and through the discharge pipe 58. Should the valve spool 47 have been moved in the opposite direction, fluid under pressure would have passed from the pipe 44 and the cannelle of the valve 47 into the pipe 56 and the chamber 55 of the cylinder 35, while fluid in the chamber 52 would have discharged through the pipe 51 into the corresponding end chamber of the valve cylinder 46 through a passage 59 centrally through the valve spool into the chamber 57 and out to the discharge 58. Because of the central passage 59 it will be noted that opposite ends of the valve cylinder have their pressures equalized, the pipe 58 being the discharge pipe for both end positions of the valve. By moving the valve 47 to its central position all traverse motion is stopped.

The feed motions of both the tool and the tracer are effected through an hydraulic circuit including the hydraulic cylinder 60, which as shown is integral with the slide 11, though of course it might be secured thereto. This cylinder 60 has a piston 61 therein, from one end of which extends a piston rod 62 through the inner end wall 63 of the cylinder 60. The other end of the piston has extending therefrom a piston rod 64 which extends through the opposite cylinder head 65. The piston is hollow and carries therein a double spool valve 66 having two valve portions, one of which controls the rate of discharge from the traverse cylinder 35, and the other of which controls the direction of motion of the slide 14 in feed or retraction and its rate.

The outer end portion of the valve 66 comprises a spool portion 70 having a cannelle 71 of variable width, being relatively narrow at one angular position and tapering outwardly widthwise to a diametrically opposite position. The discharge pipe 58 from the traverse valve cylinder 46 leads to a passage 72 extending through the piston rod 64, this passage 72 extending into the piston 61 and opening up at one end portion of the cannelle 71 which may be more or less closed off, depending upon the position of the valve 66. Another port 73, which also may be

controlled by the same cannelle 71, leads to a discharge passage 74 also extending through the piston rod 64 and communicating through a return pipe 75 with the tank 40. Depending upon the axial position of the valve 66, and also upon its angular position, the discharge from the pipe 58 may be more or less throttled by the valve 66.

The inner portion of the valve 66 consists of a spool 80 having a cannelle 81. The pressure pipe 44 leading from the source of hydraulic pressure communicates with a passage 82 through the piston rod 64, this passage leading to a central port 84 from which fluid under pressure is delivered through the cannelle 81 either through a port 85 and a passage 86 into the right hand end chamber 87 of the cylinder 60, or through a port 88 and a passage 89 to the left hand chamber 90 of the cylinder 60, thus to drive the piston 61 to the left or right, respectively, retracting or feeding the slide 14. The valve 66 has a shank portion 95 which extends through the piston rod 62 and is slideable through an end cap 96 of the piston rod 62. It also extends through a disk 97 which is seated against a shoulder 98 thereon and is held against rotation by a guide pin 99 secured thereto and slideable within a guide opening 100 in a post 101 upstanding from the outer end of the slide 14 and to which the outer end of the piston rod 62 is secured. A second beveled disk 105 is keyed to the shank portion 95 for rotation therewith and is held in position by a pair of nuts 106 threaded on the outer end of the shank 95 which bears against the adjacent edge of the tracer 25. The adjacent edges of the disks 97 and 105 may be provided with indexing marks as shown in Figure 1 which will show to the operator the angular position of the valve 66 and thus the portion of the cannelle 71 which is effective to control the passage of fluid between the passages 72 and 73. The valve 66 is pressed to the right as viewed in Figure 2 as far as possible by a coil spring 110 reacting between the cap 96 and the disk 97, this spring also acting to hold the tracer against the edge of the pattern. Thus as the tracer moves in and out with reference to the pattern, the valve 66 is given a corresponding axial motion which controls the passage of hydraulic fluid into opposite ends of the cylinder 60 and therefore moves the slide 14 in a corresponding direction.

In order that the valve 66 may remain in balanced position in so far as liquid pressure is concerned, it is provided with a central passage 115 opening out at 116 between the two valve portions and at 117 within the piston rod 62. The discharge passage 74 communicates with the outer end of the valve in the chamber 120. The openings 116 and 119 furnish the discharge passages for opposite end chambers 87 and 90 of the cylinder 60 when the cannelle 81 connects the chambers 90 and 87 of the cylinder 60 with the supply.

The action of the valve in controlling the feed and retracting motions of the tool 6 relative to the work and the tendency for similar motion of the tracer, and at the same time correspondingly controlling the rate of discharge from the traverse cylinder may be followed from an inspection of Figures 6 to 9, which show the relationships of the valve 66 for different conditions of traverse between the tracer and pattern. These figures are somewhat diagrammatic, the tracer element 25 being shown for the sake of simplicity as a part of the valve shank 95, although in the

other figures of the drawing it is not so shown. In Figure 6 the valve 66 and related parts are in the position which they would take while the tracer is tracing a portion of the pattern parallel to the direction of traverse. In this position of the valve the cannelure 81 is in such relation to the passages 83 and 89 that the hydraulic fluid may pass from the supply passage 83 into the passage 89 through a restricted port and thus somewhat slowly build up pressure within the end chamber 90 of the cylinder 60. This cannelure 81 also permits a substantially equal flow into the passage 86 and into the opposite end chamber 87 so that the piston is balanced and there is no feed or retracting motion imparted to the piston 61 and the slide 14. At the same time the cannelure 71 connects the passages 72 and 73 overlapping each by the same amount so that the discharge from the traverse cylinder 35 is least restricted. This results in the traverse being accomplished at maximum speed and without in or out feed motion of the tracer or the tool.

In Figure 7 the condition is shown wherein the tracer 25 is descending an inclination. This results in the spring 110 continuously pushing the valve 66 somewhat to the right as the traverse proceeds. This results in shutting off the passage 86 from the cannelure 81 and opening the passage 86 to cannelure 125 and discharge port 116, while it opens more fully through the cannelure 81 the pressure passage 83 to the passage 89. This results in building up a pressure in the chamber 90 in excess of that in chamber 87, the pressure in the latter being permitted to discharge through the port 116 and the passage 115. The piston 61 is now driven to the right, causing the feed of the tool into the work corresponding to the slope of the pattern along which the tracer is traversing and returning the valve toward initial relation to the piston 61. At the same time the motion to the right of the valve 66 has more nearly closed the passage 13 from the cannelure 71, thus more restricting the discharge from the traverse cylinder 35 and causing the traverse to be slowed and in reverse relation to the rate of feed of the tool toward the work. When the tracer reaches the flat face of the pattern, the conditions will then revert to that shown in Figure 6, there being then no in or out feed of the tool and tracer and the traversing speed being returned to a maximum.

If now the tracer reaches an inclined face opposite to that shown in Figure 7, as that shown in Figure 8, the valve 66 is retracted, opening the cannelure 81 more widely to the passage 86 and increasing the pressure in the end chamber 87 and opening up the passage 89 from the chamber 90 at the left hand end of the cylinder to the discharge through the port 119 and the discharge passage 115. This causes the piston 61 to be driven toward the left, which persists as long as the tracer is pushed outwardly by its engagement with the pattern. This position of the valve 66 also throttles the discharge from the passage 72 to the cannelure 71, thus decreasing the rate of flow from the traverse motor, slowing down this rate inversely proportional to the retracting speed of the tool and tracer which is determined by the extent of opening of the cannelure 81 to the passage 86 and of the passage 89 to the discharge port 119.

In case of a very sudden drop in the pattern contour as shown in Figure 9, the spring 110 acts to move the valve 66 more violently to the right as shown in this figure, this cutting off the pas-

sage 73 from the cannelure 71, completely stopping the traverse motion, while opening wider through the cannelure 81 connection between the passages 83 and 89, thus increasing the flow into the end chamber 90 while the discharge takes place freely from the chamber 87 through the passage 86, cannelure 125, and the discharge passage 116. The motion of the tracer and the tool is now entirely in feed and this persists as long as the tracer fails to meet an obstruction to its feeding motion. As soon as it reaches a portion in line with the traverse, conditions then change to that shown in Figure 6, whereupon there is no feed and the traverse resumes at maximum rate.

Attention has been called to the fact that the cannelure 71 is not of uniform width, being shown as narrow at one diametrical point and gradually increasing in width to the opposite diametrical point. By adjusting the valve member 66 angularly, the effective widthwise portion of the cannelure which controls communication from passage 72 to passage 73 may be varied as desired, thus to determine the amount of throttling of the flow relative to the traverse motor corresponding to any particular feed speed, whether in feed or retraction.

It will be seen from the foregoing that a single valve controls both the speed of traverse and the speed and direction of the feed motion which is at right angles to the direction of traverse. The valve comprising the cylinder 46 with its spool valve 47 which controls the direction of relative traverse and the valve comprising the spool portion 80 and its casing which controls the in and out feed motion are thus correlated through the control of the discharge from the traverse cylinder 35 by the valve spool portion 70 integral with the spool portion 80 in a predetermined manner to vary the relative rates of motion of the motors controlled thereby. This predetermined manner is adjustable by turning the valve 66 about its axis by turning the disk 105. The direction of traverse is controlled entirely by the operator controlled valve 47.

From the foregoing description of an embodiment of this invention, it will be evident to those skilled in the art that various changes and modifications might be made without departing from its spirit or scope.

I claim:

1. In combination, a carriage, a support for said carriage on which said carriage is movable in one linear direction, means mounting said support for motion in a linear direction perpendicular to said first mentioned linear direction, a tool carried by said carriage, a fixed template, a tracer carried by said carriage in position to move along and in contact with said template as said carriage is moved, said tracer being mounted for motion in the general direction of motion of said carriage on said support and relative to said support, an hydraulic cylinder carried by said support arranged with its axis transverse to the direction of motion of said support, a hollow piston within said cylinder, a tubular piston rod extending from said piston and secured to said carriage, a spool valve within said piston provided with a stem extending through said piston rod and bearing on said tracer, hydraulic connections to opposite ends of said cylinder and controlled by said valve causing said carriage to follow up the motion of said tracer, and means 75 operatively connected thereto for moving said

support to cause said tracer to traverse said template.

2. In combination, a carriage, a support for said carriage on which said carriage is movable in one linear direction, means mounting said support for motion in a linear direction perpendicular to said first mentioned linear direction, a tool carried by said carriage, a fixed template, a tracer carried by said carriage in position to move along and in contact with said template as said carriage is moved, said tracer being mounted for motion in the general direction of motion of said carriage on said support and relative to said support, an hydraulic cylinder carried by said support arranged with its axis transverse to the direction of motion of said support, a hollow piston within said cylinder, a tubular piston rod extending from said piston and secured to said carriage, a spool valve within said piston provided with a stem extending through said piston rod and bearing on said tracer, hydraulic connections to opposite ends of said cylinder and controlled by said valve causing said carriage to follow up the motion of said tracer, hydraulic means operatively connected thereto for moving said support, speed controlling means including said valve operatively connected to said hydraulic means.

3. In combination, a carriage, a support for said carriage on which said carriage is movable in one linear direction, means mounting said support for motion in a linear direction perpendicular to said first mentioned linear direction, a tool carried by said carriage, a fixed template, a tracer carried by said carriage in position to move along and in contact with said template as said carriage is moved, said tracer being mounted for motion in the general direction of

5 motion of said carriage on said support and relative to said support, an hydraulic cylinder carried by said support arranged with its axis transverse to the direction of motion of said support, a hollow piston within said cylinder, a tubular piston rod extending from said piston and secured to said carriage, a spool valve within said piston provided with a stem extending through said piston rod and bearing on said tracer, hydraulic connections to opposite ends of said cylinder and controlled by said valve causing said carriage to follow up the motion of said tracer, hydraulic means operatively connected thereto for moving said support, speed controlling means operatively connected to said hydraulic means and including said valve for said hydraulic means, and means operatively connected to said valve and actuated by angular adjustment of said stem for varying the control of said speed-controlling means.
